UNITED STATES PATENT OFFICE.

EDWARD B. PHELPS, OF SPRINGFIELD, MASSACHUSETTS.

MUSIC-LEAF HOLDER.

SPECIFICATION forming part of Letters Patent No. 275,696, dated April 10, 1883.

Application filed November 7, 1882. (No model.)

To all whom it may concern:

Be it known that I, EDWARD B. PHELPS, a citizen of the United States, residing at Springfield, in the county of Hampden and State of Massachusetts, have invented new and useful Improvements in Music-Leaf Holders, of which the following is a specification.

This invention relates to improvements in music-leaf holders adapted to be used on pianos, organs, &c., for holding the sheets of music in an open position before the player, the object being to provide leaf-holding devices which are easily and quickly removable from the face of the sheets to permit the latter to be turned over without obstruction, and which, when so removed, are capable of being automatically held away from said sheets, and of being by the player instantly disengaged as soon as a sheet is turned and allowed to spring against the music and retain the sheets of the latter in an open position.

In the drawings forming part of this specification, Figure 1 is a plan view of a music-leaf holder constructed according to my invention. Fig. 2 is also a plan view, but showing the spring-holder in a position away from the music. Fig. 3 is a front elevation, showing the central part of music-sheets on the holder and the position of the sheet-holding spring thereagainst when holding said sheets open. Figs. 4 and 5 are detail views.

In the drawings, A is a metallic base, provided with two vertical shaft-supports, c c. d is a shaft. h is a leaf-arm, one end of which terminates in a coil-spring, i. B is a base, of wood or other similar material, to receive in a proper recess in its face said metallic base A.

The base A is cast or otherwise made from any suitable metal, or may be made from heavy wood or any suitable material, and has fixed upon its upper face the two shaft-supports c c, the latter being perforated to receive the shaft d and support the latter by its ends in a horizontal position above the face of said base A, said shaft being rigidly secured to said supports.

The leaf-arm h is made from spring-wire, and one end thereof is provided with an eye or a hook, as in Fig. 4, through which said shaft passes loosely, so that said arm may be hung by one end thereof to oscillate on said bar d close to the inner side of one of the supports.

c. The opposite end of arm h is bent around shaft d, and extended along on the latter in the form of a spring, i, and the extreme end is secured to said shaft after drawing said spring to such a tension as will throw said arm over to the position shown in Fig. 1. The fastening of said spring end of arm h to shaft d is effected by inserting said end through a hole drilled in said shaft, or in any other convenient way. Said spring i is also crowded somewhat toward the right-hand support c, to carry the end of arm h against the latter with some force previous to fastening its end as aforesaid. The said right-hand support c is provided with a cam-shaped cut, e, or with some other suitable stop, under which the part of arm h next to said support may be pushed by spring i or its own inclination to spread when turned over to the position shown in Fig. 2, and whereby it is so held until said part of arm h is pushed away from said support. This last-named support c is provided with a projecting stop on its inner side, (lettered o,) on which arm h rests when thrown over, as in Fig. 1, and whereby it is prevented from dropping too low to conveniently allow one to place their finger under it to turn it up.

When it is found desirable to provide some material connected with the base of the holder less hard than metal, which shall come in direct contact with the polished surface of the musical instrument on which said holder is used, the base A may be let into or attached to a wooden base, B; or the supports c c may be secured to the last-named base directly, if it be heavy enough to serve its purpose.

The operation of my invention is as follows: The holder is placed on the piano or other instrument just in front of the music-rack, and the arm h is turned forward, as in Fig. 2, and when so turned spring i crowds one side of said arm against said right-hand support c, forcing it under said cam-cut e, and holding the arm from being thrown back by the action of spring i by its tendency to unwind on shaft d. The music is now placed on the rack back of the supports c c, the right-hand end of arm h is pushed slightly away from the cam-catch e, and said arm is by spring i thrown over against the sheets a a of music, holding them open, as in Fig. 3. When the player wishes to turn a leaf over he draws arm h forward, catching it

at *e*, turns the leaf, and disengages said arm, as before. What I claim as my invention is— In combination, the base *A*, having thereon the shaft-supports *c* *c*, one of which is provided with the arm-stop *o* and the curved shoulder *e*, the shaft *d*, immovably secured to the supports, the arm *h*, pivoted on said shaft *d* at one end, and at the other end bent spirally

around the shaft to form the spring *i*, whereby the arm *h* is forced against the shaft-support *c* provided with the stops, and when relieved from stop *e* will swing it on said shaft against stop *o*, substantially as set forth.

EDWARD B. PHELPS.
